UNITED STATES PATENT OFFICE.

HENRY BERGER, OF NEW YORK, N. Y.

DESIGN FOR STAR CENTER-PIECE.

Specification forming part of Design No. 5,212, dated August 22, 1871.

To all whom it may concern:

Be it known that I, HENRY BERGER, of the city, county, and State of New York, have invented a new and original Design for a Star Center-Piece; and I do hereby declare the following to be a full, clear, and exact description thereof, which will enable those skilled in the art to make and use the same, reference being had to the accompanying drawings forming part of this specification, which drawings represent a plan view of this design.

The distinguishing feature of this design is the star-shaped rim, which is ornamented by leaves situated in its depressions and partly covering said rim. The field inclosed by the star-shaped rim is ornamented by diamonds situated inside of the rays of the star, and by a central button ornamented by arabesques, and surrounded by rams' horns and spear-heads.

In the drawing, A designates a center-piece, which is ornamented by a star-shaped rim, B. The depressions a of this rim are occupied by leaves C, which partly cover the rim. The rays c of the star B are ornamented by diamonds, d,

and the center of the star is occupied by a raised button, D, ornamented as shown, and surrounded by a rim of rams' horns, e, and spear-heads f.

By these means a center-piece is obtained which is highly ornamental, and which presents a new and distinguished appearance.

What I claim as new, and desire to secure by Letters Patent, is—

1. In a center-piece, the star-shaped rim B, as shown and described.
2. The combination of leaves C with the star-shaped rim B, as shown and described.
3. The combination of the diamonds d with the star-shaped rim B, as shown and described.
4. The rim of rams' horns and spear-heads surrounding the central button D, as shown and described.

This specification signed by me this 8th day of July, 1871.

HENRY BERGER.
